UNITED STATES PATENT OFFICE.

HOWARD F. BLEDSOE AND BENJAMIN F. CRAWFORD, OF ELLENSBURG, WASHINGTON.

FLOAT-VALVE.

1,101,394.

Specification of Letters Patent.

Patented June 23, 1914.

Application filed September 10, 1913. Serial No. 789,201.

To all whom it may concern:

Be it known that we, HOWARD F. BLEDSOE and BENJAMIN F. CRAWFORD, citizens of the United States, residing at Ellensburg, 5 in the county of Kittitas and State of Washington, have invented new and useful Improvements in Float-Valves, of which the following is a specification.

This invention relates to improvements in 10 float controlled valves and has particular application to a float valve for controlling the flow of water into flushing tanks. It is to be understood, however, that our invention in its useful application is not limited to 15 this particular purpose.

In carrying out the present invention, it 20 is our purpose to provide a float controlled valve wherein, when the water has been restored to its normal level succeeding the discharge of the water from the tank or 25 reservoir, the valve will be closed quickly so as to eliminate unnecessary wear and tear on the mechanism incident to the movement of the valve to closed position with the rise 30 of the water and wherein the valve in its movement to closed position will be cushioned so that unnecessary shock to and vibration of the mechanism will be eliminated.

It is also our purpose to provide a valve 35 of the class described which will embody in its construction among other features main and supplemental or auxiliary floats, the main float being movable through a vertical arc when at its limit of downward movement 40 to open the valve and maintain a neutral position so that the valve will remain open as the water level within the tank is restored, the auxiliary float being connected with the first float in such manner as to move the latter out of neutral position when the water 45 level is restored to normal whereby the first mentioned float will be buoyed up to its normal position and close the valve with a snap.

Furthermore, we aim to provide a float 50 controlled valve which will embrace the desired features of simplicity, efficiency and durability, one which may be manufactured, installed and maintained at a minimum expense and one which will operate positively and effectively at all times and under all conditions.

With the above and other objects in view, the invention consists in the construction, 55 combination and arrangement of parts here-

inafter set forth in and falling within the scope of the claims.

In the accompanying drawings: Figure 1 is a longitudinal sectional view through a flushing tank equipped with a float valve 60 constructed in accordance with our present invention, the valve mechanism being shown in elevation. Fig. 2 is an enlarged view in elevation of the valve mechanism removed from the tank, parts being shown in section. Fig. 3 is a cross sectional view on the line 3—3 of Fig. 2. Fig. 4 is a similar view on the line 4—4 of Fig. 2. Fig. 5 is a horizontal sectional view through the valve mechanism. Fig. 6 is an enlarged perspective view of part of the valve mechanism.

Referring now to the accompanying drawings in detail, the numeral 1 designates a flushing tank of any suitable construction. Leading into the tank 1 is a supply pipe 2 75 connected up with a suitable source of water supply and disposed, in the present instance, in a vertical plane and terminating adjacent to the upper end of the tank 1. Suitably fastened to one side wall of the tank 1 80 adjacent to the upper end of the supply pipe and in communication with the latter is a casing 3 having the upper end thereof threaded exteriorly to receive a cup-shaped cap 4 provided with a finger piece 5 formed 85 with an aperture 6 adapted to receive a rod or the like so that the cap may be tightened and initially rotated to remove the same. In the present instance, the lower wall of the casing 3 is formed with an opening 7 and 90 formed with an outwardly projecting flange 8 concentrically of the opening and forming a valve seat.

The numeral 9 designates a discharge tube or pipe located, in this instance, in a plane 95 parallel with the supply pipe 2 and having the upper end thereof passed through the opening 7 in the casing 3 and capable of sliding movement relatively to the supply pipe and into and out of the casing 3. Adjacent to its upper end the tube 9 is formed with an annular series of apertures 10 whereby when the upper end of the tube is moved into the casing communication between the supply pipe and the interior of 105 the tank by way of the tube and the apertures 10 will be established, while when the tube is moved downwardly communication between such supply pipe and the tank is cut off incident to the wall of the opening 7 110

closing the openings 10. The upper end of the tube or pipe 9 is closed and upon such end is mounted a disk 11 provided with a depending centrally located stud 12 designed to threadedly engage an opening formed in the center of the closed end of the tube to hold the disk in applied position. Interposed between the disk 11 and the adjacent end of the tube is a leather washer 13 while the periphery of the disk is provided with a depending annular flange 14 surrounding the marginal edge of the leather washer and designed to prevent spreading of the latter as the washer engages the seat 8 in the downward movement of the tube. By means of this construction, it will be seen that when the upper end of the tube is lowered or moved outwardly of the casing 3, the openings 10 will shut off communication between the supply pipe and the tank, while the valve composed of the leather washer 13 and the disk 11 will engage the valve seat 8 and so form, in effect, a seal in order that leakage will be avoided.

The tube 9 is float controlled, that is to say, is elevated and lowered by means of a float controlled by the level of the water within the tank. In the present instance, a block 15 is formed with parallel openings 16, 17 through which the pipe 2 and tube 9 pass respectively. A set screw 18 threadedly engages an aperture formed in one end of the block and has the inner end thereof movable into the openings 16 to bind against the supply pipe so as to hold the block in proper position upon the pipe. Extending outwardly from one side of the block is a horizontal pivot bolt 19 upon which is rotatably mounted a disk 20 and secured upon the disk adjacent to the periphery thereof is a crank pin 21 connected through the medium of a pitman 22 with a pin 23 carried by a collar 24 surrounding the tube 9 above the block 15, and extending outwardly from the face of the block 15 above the bolt 19 is a pin 25 disposed within an arcuate shaped slot 26 formed in the disk adjacent to the periphery thereof. The outer face of the disk 20 is equipped with a socket 27 carrying an outwardly extending rod 28, and with a second socket 29 arranged in the present instance at right angles to the first socket and receiving one end of a rod 30. Upon the free end of the rod 30 is suitably secured a float 31, while extending at right angles to and fastened to the free end of the rod 28 is a post 32 receiving a collar 33 adjustable longitudinally thereon and adapted to be held in adjusted position by means of a set screw 34 and carrying a float 35.

In operation, assuming the tank to have been emptied by the opening of the valve controlling the outlet pipe, the rod 30 carrying the float 31 will be in a vertical plane

while the rod 28 carrying the float 35 will be in a horizontal plane. As the floats move to this position, incident to the discharge of water from the tank, the disk 20 is rotated and, through the medium of the pitman 22 and collar 24, raises the tube or pipe 9 so that the valve composed of the leather washer 13 and the disk 11 disengages the seat 8 while the apertures 10 in the upper end of the tube are uncovered so that the water from the supply pipe will pass into the tank 1. As the water rises within the tank 1, the float 31 remains inactive incident to the same being in neutral position and balanced by the rising water. However, as the water reaches the float 35, the latter is elevated and so overbalances the float 31 with the effect that the latter float is buoyed up by the water and rotates the disk 20 and through the medium of the pitman 22 draws the tube 9 down so that the apertures 10 are closed and the valve seated thereby cutting off the flow of water to the tank, the pin 25 and slot 26 limiting the movement of the disk under the action of the floats and so preventing vibration of the mechanism incident to the valve engaging its seat.

From the foregoing description taken in connection with the accompanying drawings, the construction and mode of operation of our improved float valve will be readily apparent.

It will be seen that the valve will be closed quickly and with a snap, incident to the float 31 remaining submerged in the water until the latter has reached its normal level and then rising to the surface of the water.

While we have herein shown and described one preferred form of our invention by way of illustration, we desire it to be understood that we do not limit or confine ourselves to the precise details of construction herein described and delineated, as modification and variation may be made within the scope of the claims without departing from the spirit of the invention.

We claim:

1. In a float valve, a supply pipe, a casing in communication with said pipe and formed with an opening, a discharge pipe slidably mounted within said opening and having apertures formed therein adjacent to the end within said casing, said discharge pipe disposed in parallelism with said supply pipe, a block fixed to said supply pipe, a disk rotatably mounted upon said block, a connection between said disk and discharge pipe, a float connected with said disk and adapted to drop and rotate the latter as the water level falls whereby the discharge pipe will be moved into the casing to establish communication between the same and the supply pipe and rise as the water

level is restored whereby the disk will be rotated to move the discharge pipe out of the casing and so cut off communication with the supply pipe, and means associated with said block and disk and acting to limit the movement of the disk under the action of said float.

2. In a float valve, a supply pipe, a casing in communication with said pipe and formed with an opening, a discharge pipe slidably mounted within said opening and having apertures formed therein adjacent to the end within said casing, said discharge pipe disposed in parallelism with said supply pipe, a block fixed to said supply pipe, a disk rotatably mounted upon said block and formed with a slot, a pin

carried by said block and disposed within said slot and acting to limit the turning movement of the disk, a connection between 20 said disk and discharge pipe, and a float connected with said disk and adapted to drop and rotate the latter as the water level falls whereby the discharge pipe will be moved into the casing to establish communication between the same and the supply pipe.

In testimony whereof we affix our signatures in presence of two witnesses.

HOWARD F. BLEDSOE.

BENJAMIN F. CRAWFORD.
